UNITED STATES PATENT OFFICE.

JAMES B. HUNTER, OF DAYTON, OHIO, ASSIGNOR OF ONE-FIFTH TO GEORGE W. HUNTER,
ONE-FIFTH TO JOHN G. COLLISON, ONE-FIFTH TO FRANK W. KREHBIEL, AND ONE-
FIFTH TO GEORGE R. EASTMAN, ALL OF DAYTON, OHIO.

FEED-WATER HEATER.

1,261,393.

Specification of Letters Patent. Patented Apr. 2, 1918.

Application filed August 2, 1915. Serial No. 43,072.

To all whom it may concern:

Be it known that I, JAMES B. HUNTER, a citizen of the United States, residing at Dayton, in the county of Montgomery and State 5 of Ohio, have invented certain new and useful Improvements in Feed-Water Heaters, of which the following is a specification, reference being had therein to the accompanying drawing.

- 10 This invention relates to feed water heaters and more particularly to a combined feed water heater and accelerator. The primary object of the invention is to provide a feed water heater of such a character that it will 15 be applicable to locomotive boilers, as well as to other boilers of various kinds, and will raise the feed water to a relatively high temperature before it enters the boiler, thereby increasing the efficiency of the boiler and reducing the amount of fuel necessary to maintain 20 the boiler at its maximum efficiency. As is well known the introduction of cold or relatively cool water into a steam boiler is highly objectionable because it not only reduces 25 the efficiency of the boiler by temporarily cooling the water therein and reducing the steam supply but it also results in unequal expansion and contraction of the parts which, in turn, quickly causes leakage. 30 Various heaters have been provided for heating the water before it enters the boiler and while some of these have a high efficiency they are not applicable to locomotive boilers and they are of an expensive construction. 35 It has been proposed heretofore to provide a feed water heater in which the feed water could be mixed with live steam from the boiler and thus heated to a comparatively high temperature before it entered the 40 boiler. These devices have, however, as far as I have been able to ascertain, been impractical and have not gone into use. One of the principal difficulties encountered was the incrustation of the heater due to the 45 deposits precipitated from hard water. These deposits accumulated to such an extent that they quickly choked up the heater.

It is, therefore, a further object of the invention to so construct and arrange the several parts of the heater that the incrustation due to deposits from hard water will be reduced to a minimum; and, further, to so

construct and arrange the parts of the heater that the steam will not only heat the feed water but will accelerate its movement toward the boiler, thereby assisting the injector, pump or other device used for forcing the feed water into the boiler. It is also an object of the invention to so construct and arrange the device that it will be automatic in its operation, and will not only start and stop without attention on the part of the operator but will also adjust itself to any variation in the amount of water supplied thereto.

In the accompanying drawings, Figure 1 is a side elevation of a boiler showing my invention applied thereto; and Fig. 2 is a longitudinal sectional view taken through the heater with a part of the heating chamber broken away.

In these drawings I have illustrated one embodiment of my invention and for the purpose of illustration have shown the same as applied to an ordinary horizontal steam 75 boiler but it will be understood that it is applicable to various types of boilers and that the arrangement shown may be varied to accommodate the same to varying circumstances.

In these drawings the boiler is shown at 1 and is provided with the usual steam dome 2. A feed water line 3 leads to the boiler and has interposed therein an injector 4 of ordinary construction which is operated by steam from the boiler, it being for this purpose connected with the steam dome by a pipe 5. While I have shown an injector of ordinary construction as the means of supplying the feed water 90 to the boiler it will be understood that a pump or any other suitable device can be used for this purpose, it being only necessary that the water shall be supplied to the heater, as hereinafter described, under a 95 proper pressure.

In carrying out my invention I have interposed my combined feed water heater and accelerator in the feed water line between the injector and the boiler. The device as 100 here shown comprises a water nozzle 6 which is connected with the feed water pipe 3 and has a reduced discharge opening arranged to discharge a jet of water into a heating

chamber. This heating chamber may be of any suitable character, but is preferably of a diameter considerably greater than the diameter of the jet of water from the water nozzle and is here shown as a coil of pipe 7, the discharge end of which is connected with the boiler, as shown at 8. Means are provided whereby the jet of water which is discharged from the water nozzle 6 will, during its passage to the heating chamber, be enveloped in a jet of steam which will keep the water out of contact with the walls of the device. In the present construction I have provided a steam nozzle 9 connected by means of a pipe 10 with the steam dome and having a tapered portion 11 surrounding and spaced away from the water nozzle to form a condensing chamber about the latter. The discharge end of the steam nozzle extends some distance beyond the discharge end of the water nozzle and is provided with a passageway 12 of a diameter slightly greater than the diameter of the discharge opening of the water nozzle. This passage forms a conducting passage or chamber through which the steam and water are discharged into the heating chamber 7. Preferably, this conducting chamber is of uniform diameter for a portion of its length, but has that end adjacent to the heating chamber flared slightly. The space 12 between the conducting chamber and the end of the water nozzle may be characterized as an accelerating chamber. The steam nozzle being in open communication with the boiler, through the steam dome, is of course subject to the pressure of the steam within the boiler and this steam being partially condensed in the condensing chamber, by its contact with the water nozzle 6, acquires a high velocity so that when it passes the discharge end of the water nozzle it has a velocity greater than the velocity of the jet of water. Inasmuch as the condensing chamber completely surrounds the water nozzle it will be apparent that the jet of water will be completely enveloped by the jet of steam, which, of course, will be hollow. Consequently, the jet of steam will carry the jet of water along with it and the movement of the latter will be accelerated. Thus the steam nozzle combines within itself the functions of condensing the steam, focusing its energy to cause it to be discharged at a high velocity, and accelerating the water by its contact with the rapidly moving steam. The device is so constructed that the intermingling of the steam and water prior to their introduction into the heating chamber will be reduced to a minimum and will be confined to the outer surface of the water jet. This is accomplished by so constructing and arranging the water nozzle and the steam nozzle as to prevent the establishment of cross currents. For this pur-

pose the discharge end of the nozzle is provided with a water passage 13 of substantially uniform diameter which causes the water jet to be discharged in a substantially cylindrical form and prevents any material spraying of the water. The tapered portion of the steam nozzle is shown as terminating on a line substantially coincident with the end of the water nozzle. That portion of the steam nozzle which extends beyond the water nozzle is provided with an annular shoulder 14 which constitutes an obstruction to the passage of the jet of steam which, when discharged from the condensing chamber, is converging upon the jet of water. The jet of steam is thus prevented from intersecting the jet of water and no serious cross currents are established. The shoulder or obstruction may be formed in various ways but I have, in the present instance, formed the conducting chamber 12 of a tube which fits snugly within the end portion of the steam nozzle and the end of which forms the annular shoulder of that nozzle. Preferably, this shoulder is adjustable to accommodate the device to varying conditions and to this end I have shown the tube as screw-threaded as shown at 14' into the end of the steam nozzle.

When the boiler is under steam pressure and the injector is operated to cause a jet of water to be discharged from the water nozzle 6 the steam within the condensing chamber of the steam nozzle will be partly condensed and will be discharged past the end of the water nozzle at a high velocity. The amount of steam in the chamber is much in excess of the condensation and this excess steam surrounds and completely envelops the jet of water which is discharged from the nozzle. The water is thus kept out of contact with the walls of the steam nozzle and conducting chamber and is carried through the conducting chamber 12, which is slightly larger than the discharge end of the water nozzle, at an increased speed due to the greater velocity of the steam. The heater thus acts as a booster for the injector or pump and by relieving the latter of part of its work enables it to operate satisfactorily under more widely varying conditions than it otherwise would do. Due to the shape and arrangement of the parts described the jet of steam will not intermingle with the jet of water and there will be but little mixing of the water and steam in the nozzle and conducting chamber. Consequently, there will be but a small precipitation of deposits and these deposits will, for the most part, be prevented from reaching the walls of the device by the enveloping jet of steam. As a result there will be no incrustation of the device such as would prevent its successful operation. The jets of water and steam are discharged from the conducting chamber 12 into the heating

chamber and because of the greater diameter of this chamber are there intermingled, the length of the chamber preferably being such that there will be a thorough intermingling 5 of the steam and water and consequent heating of the water before the latter is discharged into the boiler. The precipitation of foreign matter in the relatively large elongated heating chamber will not readily 10 obstruct the passage of the fluids through the same, and the incrustations are more easily removed from the heating chamber than from the boiler.

As will be noted the operation of the 15 device is wholly automatic. It requires no manipulation of valves and no adjustments either to start, stop or regulate the same. A check valve 15 prevents the steam from passing to the injector when the latter is inoperative. As long as no water is passing through the water nozzle there is little or no condensation in the condensing chamber and the steam will acquire no velocity. As soon as 20 the water begins to flow through the nozzle 25 condensation takes place and the steam is discharged from the condensing chamber in such a manner as to surround the water jet and to accelerate its movement.

It has been found by tests in actual service 30 on a railroad locomotive that when the steam temperature in the boiler is 370° F. the feed water will be heated by my heater to 320° F. prior to its discharge into the boiler. The high temperature of the feed water at the 35 time it is discharged into the boiler practically prevents the unequal expansion and contraction of the parts of the boiler. The device is of particular advantage on railroad locomotives because the conditions under 40 which they operate are such that it is frequently necessary to inject large quantities of water into the boiler and when these are not provided with a water heater, this water is necessarily cold or at best only partially heated. A railroad locomotive, the 45 boiler of which it had been necessary to calk daily, has since the installation of my heater thereon been operated for periods as long as three weeks without being calked, the conditions under 50 which the locomotive operated being the same in both instances.

Further, the raising of the feed water to a high temperature before it enters the boiler materially increases the heating efficiency 55 of the boiler and makes a saving in the amount of fuel consumed. The saving of fuel actually takes place in spite of the fact that live steam is used to heat the water, it having been demonstrated in actual 60 service that a locomotive equipped with this device used from eight to ten tons of coal on a run which prior to the installation of my heater required from thirteen to fifteen tons, the mileage and tonnage being, of course, the same in both instances.

This was partly an indirect saving because boiler ills were cured by the use of the heater, and partly a direct saving because the heater increased the heating efficiency of the boiler. This increase in efficiency and 70 decrease in the amount of fuel required is due to the fact that the process of heating water to a given temperature by convection gains in efficiency as the temperature of the water to be used rises above that of its maximum density. Water when continuously heated at a uniform rate from the freezing point at first contracts and then expands at a rapidly increasing rate, the co-efficient of expansion of the water increasing as the 75 temperature rises above the maximum density. Water acquires more rapidly heat which causes greater expansion because its diathermancy is increased at the higher temperature. A greater rate of expansion causes more active convection currents, and the more active convection currents increase the rate at which heat is taken up from the boiler surfaces because more water to be heated is brought into contact with the heated 80 surface in a given length of time. The more active convection currents in turn tend to break up or diminish the thickness of the non-conducting film of water which adheres to the heated metal surface, and, 85 consequently, the heat resistance caused by this water film is diminished. Consequently, a less amount of heat is required to raise the temperature of the water a given number of degrees at a high temperature than to 90 raise the temperature a corresponding number of degrees at a lower temperature. The rate at which the heat is taken up from the heated surface of the boiler, by convection, increases rapidly with the rise in temperature of the water in contact with that surface and when the water is kept at a high temperature by the use of the feed water heater the more active convection currents 95 which result take in more rapidly the heat 100 created by combustion. The heat thus acquired more rapidly at the higher temperature of the water in the boiler is transferred without material loss to the feed water in the heating chamber. Therefore, a larger 105 percentage of the heat derived from the fuel becomes transformed into power available for use in the engine and a very material gain in heating efficiency is made.

While I have shown and described one 120 embodiment of my invention I wish it to be understood that I do not desire to be limited to the details of construction shown and described, for obvious modifications will occur to a person skilled in the art, and I further wish it to be understood that the construction and arrangement of parts herein shown and described actually produce the results stated regardless of the accuracy of the theories advanced.

Having thus fully described my invention, what I claim as new and desire to secure by Letters Patent, is:—

1. In a device of the character described, a water nozzle having an orifice, a steam nozzle surrounding said water nozzle and forming therewith a tapering condensing chamber, an accelerating chamber forming a continuation of said steam nozzle in front 5 of said water nozzle and of a diameter greater than said orifice, an annular shoulder in front of said water nozzle and lying in the path of the steam issuing from said condensing chamber, a heating chamber, and 10 a conducting chamber of a diameter greater than said orifice lying to the rear of said shoulder and connecting said accelerating chamber with said heating chamber.
2. In a device of the character described, a water nozzle having an orifice, a steam nozzle surrounding said water nozzle and forming therewith a tapering condensing chamber, a heating chamber, a tubular portion 15 connecting said heating chamber with said steam nozzle, forming a continuation of the latter and of a diameter greater than the orifice of said water nozzle, a tube located in said connecting portion spaced from the end of said water nozzle and 20 provided with a passageway forming a conducting chamber of uniform diameter and of a diameter greater than said orifice, the inner end of said tube forming a shoulder lying in the path of the steam issuing from said 25 condensing chamber.
3. In a device of the character described, a tapered water nozzle having an elongated orifice of uniform diameter, a tapered steam nozzle surrounding said water nozzle and forming therewith a tapering condensing chamber, a heating chamber, a cylindrical accelerating chamber of a diameter greater than the diameter of said orifice and forming a continuation of said steam nozzle in front of said water nozzle, an annular shoulder spaced from said water nozzle and lying in the path of the steam from said condensing chamber, and a reduced passageway having a portion of uniform diameter and of a diameter greater than the diameter of said 30 orifice lying to the rear of said shoulder and connecting the accelerating chamber with the heating chamber.
4. In a device of the character described, a water nozzle having an orifice, a steam nozzle surrounding said water nozzle and forming therewith a tapering condensing chamber, a cylindrical accelerating chamber of uniform diameter forming a continuation of the steam nozzle in front of said water 35 nozzle and of a diameter greater than the orifice of said water nozzle, a heating chamber, and a conducting chamber having a portion of uniform diameter less than the diameter of said accelerating chamber and of a 40 diameter greater than the orifice of said water nozzle and connecting said accelerating chamber with said heating chamber.

In testimony whereof I affix my signature.
JAMES B. HUNTER.
